UNITED STATES PATENT OFFICE

171,541

ILLUMINABLE FONT

Sam W. Hailey, Indianapolis, Ind.

Application April 20, 1953, Serial No. 24,579

Term of patent 14 years

(Cl. D29—23)

To all whom it may concern:

Be it known that I, Sam W. Hailey, a citizen of the United States, residing at Indianapolis, in the county of Marion and State of Indiana, have invented a new, original, and ornamental Design for an Illuminable Font, of which the following is a specification, reference being had to the accompanying drawings, forming a part thereof.

In the drawings:

Figure 1 is a side elevational view of an illuminable font, showing my new design with the broken line disclosure of candles included for illustrative purposes only;

I claim:

The ornamental design for an illuminable font, substantially as shown and described.

SAM W. HAILEY.
